UNITED STATES PATENT OFFICE.

BERNHARD ZWILLINGER, OF NEW YORK, N. Y.

APPARATUS FOR CONVERTING BEEHIVE-OVENs INTO BY-PRODUCT COKE-OVENs.

1,269,895.

Specification of Letters Patent. Patented June 18, 1918.

Application filed July 12, 1917. Serial No. 180,112.

To all whom it may concern:

Be it known that I, BERNHARD ZWILLINGER, a citizen of the United States, residing in the city, county, and State of New York, have invented certain new and useful Improvements in Apparatus for Converting Beehive-Ovens into By-Product Coke-Ovens, of which the following is a specification.

My invention relates generally speaking to bee hive ovens, known in the art as standard bee hive ovens, for the production of metallurgical coke. As is well known, ovens of this class are operated in such manner that the raw gases evolved from the coal are burned by the aid of air entering into the interior of the oven to support the process of coke making, whereby all valuable by-products are destroyed, and a considerable part of the coal, including its volatile constituents, is consumed.

It is also well known that bee hive ovens can be specially constructed and operated to recover by-products but new ovens must be specially built for this purpose.

By my novel construction, however, I avoid all the above disadvantages. The principal object of my invention is to change or convert any existing bee hive or simple coke oven which produces only coke and in which the gases issuing from the coal charge are burned in the interior of the oven in order to produce the required heat for coking, into an oven in which not only coke is made but all the by-products contained in the crude gases, such as ammonia, tar, benzol, heating gas, emanating from the coal are distilled and saved.

Another object of my invention is to change any existing bee hive oven into an oven with by-product recovery without destroying its structure, or dismantling the plant or its general arrangement and to accomplish this quickly and at a low cost.

Another object of my invention is to heat the bottom of the by-product bee hive oven in a manner to carbonize the material uniformly and heat the oven sole to a higher degree in those parts where more coal lies and less in those parts where there is less coal.

Another object of my invention is to apply a method of combustion to by-product bee hive ovens by which the heat of the burned gases can be regulated controlled and distributed over the entire heating surface with higher efficiency than heretofore known

in bee hive ovens, reducing the time for carbonizing the coal charge and increasing the capacity of the oven and obtaining the by-products from the coal.

60

One or more embodiments of my invention are illustrated in the accompanying drawings in which:

Figure 1 shows a vertical cross section through one of the ovens, a portion of the back of the adjacent oven being likewise indicated.

Fig. 2 is a horizontal cross-section through Fig. 1 showing more particularly the distribution of the flues under the floor of the oven.

Fig. 3 illustrates a battery of well known forms of bee hive coke ovens arranged back to back in rows which is converted by my invention into a by-product oven battery.

75

Fig. 4 is a diagrammatic plan of a plurality of ordinary bee hive ovens arranged in rows back to back and staggered as indicated with means for supplying the heating mixture to and discharging the gases from the front of the ovens.

Fig. 5 is a detail cross section of the preheater for the air on line X—X of Fig. 4.

Fig. 6 is a cross section on line Y—Y of the preheater passageway in Fig. 4.

85

Fig. 7 is a detail view broken away at the elbow of the preheater waste gas passageway shown in Fig. 4.

Fig. 8 is a view of one of the floor bricks provided with a gas tight tenon or joint.

90

Fig. 9 is a cross-sectional view of a modified form of preheater hot air and waste gas flues.

Fig. 10 is a front view of Fig. 9.

Fig. 11 is a detail front view of the gas and air admission pipes shown in Fig. 2.

In carrying out my invention I convert the ordinary battery of bee hive ovens such as shown in Fig. 3 into by-product ovens as follows: The ordinary oven consists of vaulted fire brick chamber 1 with dome like circular walls 100 constructed on a suitable foundation 2 with an inclined flat tile bottom 3 and an opening 4 through the top. An arched door 5 is provided at the bottom of the oven through which the coke is removed and which in operation is tightly closed. A battery of these ovens is arranged in rows back to back and may be staggered as shown in Fig. 4, the fronts of the ovens being incased in suitable walls 7 on foundation 8, and the ovens being covered

100

105

110

by a non-heat-conducting backing 9 which covers the sides between the ovens and covers their tops. Tracks 200 on suitable track supports or pillars are provided for the lorries used to charge the ovens. The ovens may be arranged in a single row, in which case a large non-heat-conducting backing is arranged on top of and in back of the ovens. It will be understood, therefore, that 5 in the best embodiment of this invention the ovens which are converted are of the standard domed form and also of standard spacing from center to center.

In accordance with my invention I first 15 excavate underneath the bottom of the ovens so as to provide a space to be used for the combustion flues. Denoting the place occupied by the oven door as the front, the opposite end the rear, and the left and right 20 as sides of the oven, I excavate at the front, rear and sides so as to leave underneath the shell of the bee hive oven a space for the combustion flues with the front of the excavation somewhat lower than the rear. 25 This is clearly shown in Fig. 1. I cover the bottom of the excavation by a suitable fire brick floor 10.

A series of flues for distributing and burning a mixture of air and gas is provided beneath the oven. Their form may be widely varied. These flues have their own inlets 30 for hot air and gas and their own discharge for waste gases and are entirely separate from the interior of the oven, that is to say 35 the coke chamber. In the particular embodiment of the invention illustrated I make use of a floor 11 above the floor 10 to provide a space for the flues, the charge to be coked resting upon the floor 11. The floor 40 11 is composed of fire brick, preferably made of silica material. In order to produce a gas tight flue so as to prevent leakage, the tiles are provided with tongues 12 and grooves 13, see Fig. 8, fitting into each other, 45 the tongue and groove joints extending in a direction across the flue channels, transversely of the flue walls.

The flue system is so arranged as to be divided substantially in the middle by a division wall 14 running down the center and separating the flue system into two separate or equal halves. A plurality of vertical walls 15 arranged as indicated on each side of the central wall provides a plurality of 50 flues which carry the heating gases in a serpentine manner along the entire bottom of the ovens, compelling them to give up their heat so that the sole of the oven through its entire extent is subjected to the 55 heating of the burning gases.

In accordance with my invention and so as not to interfere with the backs of the oven and without altering the walls of the oven chambers or the spaces between the 60 ovens, I provide means for discharging the

waste, burnt gases at the front of the oven underneath the wharf of the oven. As illustrated I make use of flues 16, 17 one located at each side of the oven, the flues projecting underneath the wharf 18 at the front 70 of the oven downwardly into the longitudinal waste gas main 19. Air and gas are admitted to the combustion flues at the front through a sealing block 20, the block fitting against the ends of the walls 14 and 15 of the flues as shown in Figs. 1 and 2 and hermetically sealing the ends of the flues. A plurality of gas admission ports 21 pass through the block and are supplied with gas 75 through a gas supply pipe 22, one on each side of the oven, the fuel gas coming from the gas main 23.

Beneath the gas ports 21 are a plurality of air ports 25 which receive their supply of preheated air from the top air channel 26 of a recuperator, of which the waste-gas main 19 is a part. The air ports 25 are connected with the recuperator by a flue 24 and a header or air-box 24^a. It will be observed that there are two air inlets 25 adjacent the 80 center of each oven at opposite sides of the division 14, and two gas inlets 25 similarly situated. In addition to these other pairs of air and gas ports open into the two halves of the set of flues between the center inlets 85 and the lateral waste-gas conduits 16. The top and bottom channels 26 of the recuperator are connected at one end by passage 32 (Fig. 4) and lie above and below the intermediate chamber 19 receiving the waste 90 gases. Referring to Fig. 2 it will be observed that the gas inlets 21 are arranged above the air inlets 25 by means of which an intimate mixture is accomplished. The air being highly preheated before entering 100 into the combustion flue is expanded to a large degree and its specific gravity is therefore considerably below the specific gravity of the heating gas which enters the combustion flue at a comparatively low temperature. As a consequence thereof the gas molecules will fall into the ascending highly heated air current producing a desirable mixture, thus effecting complete combustion. The end air ports 25 are inclined somewhat 105 upwardly and are directed toward the end gas supply conduits—while the two central ports and the gas outlets run parallel to each other, thus producing a shorter flame at the end ports and elongated flames at the intermediate ports. By providing a number of 110 gas and air inlets at the front of the oven I avoid a prejudicial accumulation of heat at one restricted space and divide and separate the air and gas into small quantities for better mixing and combustion. Suitable valves and slides 300 are used in the air and gas admission passages and in the discharge pipes for waste gases for controlling the 115 supply and discharge.

Various forms of preheaters may be used for preheating the air. Figs. 1, 2 and 4 show a preheating device in which the air from the atmosphere enters into the bottom 5 air chamber 26 travels the entire length of the oven battery, ascends to the upper chamber 26 from where it goes through distributing conduit 24 into the combustion chamber. This preheater is of the recuperator 10 type, the air and waste-gas passages being separate and distinct, and the heat being transferred from the gases to the air through the intermediate wall. The flow of burning gases through the two halves of the 15 set of combustion flues beneath the floor of each oven is constant in direction, and it will be observed that the waste-gas educts 16 are of greater aggregate area than the air inlets 25, so as to allow for the expansion of 20 the gaseous contents and to avoid back-pressure. The combination of the divided set of combustion flues beneath the floor of each oven, the recuperator, and the arrangement of air and gas inlets and waste-gas outlets 25 of the floor flues whereby the burning takes place from a plurality of points, enable me in a simple manner to secure a distributed uniflow heating for the ovens which is very 30 advantageous for uniform coking.

The recuperator extends longitudinally beneath the wharf, where its installation does not require alteration of the oven structure and where it constitutes no obstruction to the operations which are carried out in 35 front of the ovens. According to my invention the heating system, which converts the ordinary simple internal combustion ovens into externally heated by-product ovens, is practically in its entirety disposed 40 below the floor levels, beneath and outside of the ovens, the construction being such as to enable the transformation to be made at low cost and with the least amount of change in the structure of the ovens, and to secure 45 highly efficient heating.

Attention may be called to the fact that, as is customary, the floors of the ovens slope downward to the front to facilitate discharge of the coke. Consequently, after the 50 ovens are charged and the coal leveled parallel with the base, the layer is from 6 to 8 inches higher at the fronts of the ovens than at the back. The hot air and gas for combustion being admitted to the under- 55 floor combustion flues at the front, the most intense heat is produced where the coal is deepest, thus further insuring uniform carbonization of the charges.

While the air for combustion can be supplied by chimney draft I prefer, for better regulation and in order to be independent of atmospheric conditions to use a fan 301 attached in the lower air channel 26 to furnish the air.

Means are provided for recovering the by- 60 products from the oven. As illustrated, I make use of a discharge pipe 27 connected by means of the charging conduit 28 with the top of the oven forming the charge opening of the oven. The conduit 28 is covered 70 by a removable cover 280 which is taken off when charging the oven through the charging conduit. A down-take pipe 29 discharges the by-products into a hydraulic main 30 where they are led off for recovery. 75

It will be observed by reference to the drawings that a battery of ordinary bee hive coke ovens are converted by my invention into closed by-product retort coke ovens without destroying or impairing the dome-like walls of the ovens and without it being necessary to rebuild the ovens so as to make them of a special shape or special construction, and without dismantling the plant or its general arrangement. The space 31 between the adjacent backs of the oven is not interfered with nor is the bank or heat protecting material 9 on the top of the oven altered nor are the track pillars and tracks interfered with or displaced. By reference 80 to Figs. 1, 3 and 4, the construction necessary to convert a battery of bee hive ovens of the ordinary form into by-product ovens will be readily understood. Referring more particularly to Fig. 4 preheated air is supplied through pipes 24 to the fronts of the ovens and the waste gases are taken away from discharge pipes 16 and 17. The recuperator is arranged along each side of the 85 fronts of the ovens under their respective wharves, the top and bottom passages 26 of the recuperator being connected at the end by an up-take pipe 32. Air is admitted from the atmosphere into the pre-heater by means of openings 33. In this way the air comes 90 from one end of the heating passage of the recuperator travels its entire length, passes upwardly through the up-take pipe 32 and then along the top passage 26 of the recuperator finding its way to the passage 24. 95 The waste gases discharged in the in-between section 19 of the recuperator are carried out by means of branch pipes 35 and the chimney 36.

In the modification shown in Figs. 9 and 10, the oven 40 is shown back to back to a corresponding oven 41 partly shown. The oven is excavated to a lesser depth than in the main figure and the bottom 42 provided as before. The top of the heating flue system 43 is raised above the wharf line 44. The floor 43 and the bottom of the oven may be placed at any convenient heights within the oven. The discharge products are carried through pipes, 45, 46, 47, 48 as before, 115 pipe 48 being supported on its shelf 49. The front of the oven is closed by a suitable door 50. The recuperator passages are arranged side by side, the central one 51 receiving the 120 waste gases from discharge pipes 52. The 125

- two side sections 53 of the recuperator are connected to and carry the air from the atmosphere around the heating chamber 51 on its way to the front of the oven. Gas is supplied to the front of the oven through a horizontal gas main 54 to which are connected a suitable number of gas pipes 55. The air is fed to the front of the oven from the branched conduit 56.
- 10 Having thus described the construction the operation will be clear. The atmospheric air enters at the ports 33 passes through the low air connecting channel 26 and along the length of the bench ovens underneath the 15 wharf, flows to the uptake passage 32 to the upper air distributing channel 26, this being connected by air conduits through orifices in the front wall of the oven as indicated and from this point the air is led into the combustion flues. The heating gas is conducted through the gas pipes 23, 22 and 21 into the front of the oven so that when the gas and air meet they are burned and their products circulated through the flues escaping up the 25 discharge pipes 16 and 17 into the common discharge flues 19.
- In beginning the operation of a battery of ovens one or a small number of ovens is first heated by burning coal or producer gas so 30 that the wall of the oven and a part of its shell retains sufficient heat. The oven is then charged with coal through the door, the gases are expelled from the coal and pass out through the passageways 27, 28 at the top of 35 the oven, are collected in a suitable holder after having been deprived of their tar and ammonia contents may be conducted to the return gas main 23. At this time air is admitted to produce combustion. After a few 40 ovens have been put into operation in the described manner the remaining number of ovens can be prepared for permanent operation by charging coal through their charging conduits at the tops of the oven or through 45 the oven doors. For permanent operation the ovens are of course tightly closed against the entrance of air, acting wholly as retorts with external heating. Heating gas may be obtained from the first ovens in actual operation instead of preparing for distillation by 50 the combustion of fuel in the interior of the oven. When the ovens are in regular operation the gases from the distilled coal then escape through the take off pipe on top of 55 the dome and are worked up in the usual manner for by-products.
- What I claim and desire to secure by Letters Patent is:
1. The combination with the walls of a 60 row of coke ovens of bee hive design, and a wharf extending longitudinally in front of the same, of means for taking off by-products from the ovens, sets of combustion flues arranged beneath the floors of the ovens 65 with their passages separate from the in-
  - terior thereof, a preheater extending lengthwise beneath the wharf, pipes for supplying said combustion flues with heating gas, and hot-air and waste-gas conduits extending outward and generally forward from the 70 floor flues of the respective ovens to the preheater beneath the wharf, whereby the row of bee hive ovens is constituted a row of closed, by-product retort ovens.
  2. The combination with the walls of a 75 row of coke ovens of bee hive design, and a wharf extending longitudinally in front of the same, of means for taking off by-products from the ovens, sets of combustion flues arranged beneath the floors of the ovens with 80 their passages separate from the interiors thereof, a preheater extending lengthwise beneath the wharf and having separate and distinct passages in heat-exchange relation for air and waste gases, pipes for supplying 85 said combustion flues with heating gas, and hot-air and waste-gas conduits extending outward and generally forward from the floor flues of the respective ovens and connecting the same with the air and waste-gas 90 passages respectively of the preheater beneath the wharf, the area of the waste-gas conduits discharging from the combustion flues being greater than that of the hot-air supply conduits, whereby the row of bee hive 95 ovens is constituted a row of closed, by-product retort ovens having uniflow heating.
  3. The combination with the walls of a 100 row of coke ovens of bee hive design, and a wharf extending longitudinally in front of the same, of means for taking off by-products from the ovens, sets of combustion flues arranged beneath the floors of the ovens with their passages separate from the 105 interiors thereof, a preheater extending lengthwise beneath the wharf, hot-air and waste-gas conduits extending outward and generally forward from the floor flues of the respective ovens to the preheater beneath the 110 wharf, there being waste-gas educt conduits toward both sides of each oven and hot-air supply conduits approximately at the center and pipes for supplying heating gas to the combustion flues adjacent the outlets 115 thereto of the hot-air conduits, whereby the row of bee hive ovens is constituted a row of closed, by-product retort ovens having divided uniflow heating.
  4. The combination with the walls of a 120 row of coke ovens of bee hive design, and a wharf extending longitudinally in front of the same, of means for taking off by-products from the ovens, sets of combustion flues arranged beneath the floors of the ovens 125 with their passages separate from the interiors thereof, a preheater extending lengthwise beneath the wharf, there being waste-gas educt conduits toward both sides of each oven, hot-air supply conduits approximately at the 130

- center and additional hot-air supply conduits between these and the lateral waste-gas conduits and pipes for supplying heating gas to the combustion flues adjacent the outlets thereto of the several hot-air conduits, whereby the row of bee hive ovens is constituted a row of closed, by-product retort ovens having distributed uniflow heating.
5. The combination with a bee hive coke oven structure, of a set of combustion flues beneath the floor of the oven, said set of flues being divided in lateral halves and having their passages separate from the interior of the oven, an external preheater, hot-air and waste-gas conduits extending outward from the floor flues to the preheater, there being waste-gas educt conduits toward both sides of the oven and hot-air supply conduits approximately at the center at opposite sides of the division, and pipes for supplying heating gas to the combustion flues adjacent the outlets thereto of the hot-air conduits, whereby the oven is constituted a closed, by-product retort oven having divided uniflow heating.
6. The combination with a bee hive coke oven structure, of a set of combustion flues beneath the floor of the oven, said set of flues being divided in lateral halves and having their passages separate from the interior of the oven, an external preheater, hot-air and waste-gas conduits extending outward from the floor flues to the preheater, there being waste-gas educt conduits toward both sides of the oven, hot-air supply conduits approximately at the center at opposite sides of the division and additional hot-air supply conduits between these and the lateral waste-gas conduits, and pipes for supplying heating gas to the combustion flues adjacent the outlets thereto of the several hot-air conduits, whereby the oven is constituted a closed, by-product retort oven having distributed uniflow heating.
7. The combination with the walls of a row of bee hive coke ovens, of sets of combustion flues arranged beneath the floors of said ovens and sealed from the interiors thereof, pipes for supplying heating gas to said flues beneath the ovens, a recuperator comprising separate and distinct air and waste-gas passages located outside of and along the battery, hot-air conduits entering the floor flues of the ovens from the air passage of said external recuperator, conduits of greater capacity for discharging the products of combustion from the floor flues outside the row and into the waste-gas passage of the recuperator, and an offtake conduit connected to the top of each oven for delivering by-products from said oven, whereby said bee hive ovens are constituted closed, by-product retort ovens having uniflow heating.
8. The combination of the walls of a battery of circular bee hive coke ovens of standard design arranged in two rows with their backs adjacent, means for recovering by-products from the tops of said ovens, sets of combustion flues beneath the floors of the ovens and sealed from the interiors thereof, conduits arranged outside of said ovens for supplying air and gas to said flues from the front to be burned under the floors of the ovens and means for discharging the burnt gases from said flues outward at the fronts of the respective ovens, whereby said bee hive ovens are constituted closed, by-product retort ovens.
9. The combination with a non-recovery bee hive coke oven, of means for recovering by-products from said oven, air passages for supplying air to the front of the oven, gas passages for supplying gas in proximity to the outlets of the air passages, means for pre-heating air arranged at the front of the oven, flues for burning air and gas mixture under the floor of the oven, and discharge flues for discharging the burnt gases at the front of the oven, into the air preheating device.
10. The combination with an original bee hive coke oven structure with its original walls, of combustion flues arranged beneath the floor of the oven and sealed from the interior thereof, external ducts for supplying said flues at the front with air and gas for combustion, conduits for discharging the waste gases from said combustion flues at the front and outside of the oven, and an offtake connected with the top of the oven for delivering by-products therefrom, the oven being sealed, whereby the coke oven structure is converted into a closed, by-product retort oven.
11. The combination with the walls of a bank of coke ovens, of sets of combustion flues arranged in the bottoms of the ovens and having a division between the lateral halves of the set of flues of each oven, gas and air inlets at the fronts of the ovens and at both sides of said divisions, waste-gas flues extending forward from the two halves of each set of flues at opposite sides of the air and gas inlets, and a preheater extending beneath the wharf in front of the ovens and connected with said air inlets and forwardly extending waste-gas flues.
12. The combination with a battery of original internal combustion coke ovens with their original walls, of conduits for carrying off by-products from their tops, sets of combustion flues beneath their floors, an air preheater extending lengthwise exterior to the battery and below the floor levels, underground hot-air and waste-gas conduits connecting said combustion flues with the external preheater and pipes for supplying heating gas to said combustion flues in proximity to the outlets thereto of the hot-air supply conduits, whereby the battery of

ovens is converted into a bank of closed, by-product retort ovens, the ovens being sealed.

13. The combination with a double row battery of original bee hive coke ovens with their original walls, and wharves extending lengthwise of the battery in front of the ovens, of sets of combustion flues arranged beneath the floors of the ovens and sealed from the interiors thereof, a preheater extending lengthwise outside, in front of each row of ovens and beneath the oven wharf, hot-air and waste-gas connections at the base of the battery extending from each preheater to the forward part of the combustion flues of the several ovens of the corresponding row, gas pipes likewise entering the forward parts of said flues from the front, and means for taking off by-products from the ovens, the ovens being sealed, whereby the battery of bee hive ovens is converted into a battery of closed, by-product retort ovens.

14. The combination with a battery of two rows back-to-back of original bee hive coke ovens with their original walls, of sets of combustion flues arranged under the floors of the ovens, conduits for supplying said flues with air and gas for combustion and conduits for conducting away the waste gases

therefrom, said air supply and waste-gas educt conduits extending at the front and exteriorly of the ovens, means for taking off by-products from the ovens, and means for preheating the air, whereby the battery of bee hive ovens is converted into a battery of closed, by-product retort ovens, the ovens being sealed.

15. The combination with an original non-recovery bee hive coke oven structure with its original walls, of a floor and a system of combustion flues arranged thereunder, means for taking off by-products from the top of the oven, external conduits for supplying the floor flues with air and gas for combustion and for conducting away the waste gases therefrom, and means for preheating the air, whereby the coke oven structure is converted from a non-recovery bee hive coke oven structure into a closed by-product retort oven, the oven being sealed.

In testimony whereof I have signed my name to this specification, in the presence of two subscribing witnesses.

BERNHARD ZWILLINGER.
